WATER HEATER CONTROL

Henry C. Keck, Pasadena, and Theodore J. Dykzeul,
Rolling Hills, Calif., assignors to Robertshaw-Fulton
Controls Company, Richmond, Va., a corporation of
Delaware

Filed Feb. 15, 1960, Ser. No. 59,411

Term of patent 14 years

(Cl. D52—6)

FIG. 1 is a perspective view from the right of the water heater control showing our new design;

FIG. 2 is a perspective view from the left of the water heater control; and

FIG. 3 is a side elevation of the knob on the lower front of the device shown in FIGS. 1 and 2.

The rear of the water heater control is conventionally plain.

We claim:

The ornamental design for a water heater control, as shown and described.
